United States Patent Office

Des. 187,501
Patented Mar. 22, 1960

187,501

BOTTLE HOLDER

Magnus Hagenes, Brooklyn, N.Y.

Application October 30, 1959, Serial No. 58,139

Term of patent 14 years

(Cl. D58—26)

Fig. 1 is a front perspective view of a bottle holder showing my new design;

Fig. 2 is an elevational view of one side thereof;

Fig. 3 is an elevational view of the other side thereof; and

Fig. 4 is a top plan view thereof.

The bottle shown in broken lines in Figs. 1 and 3 is for illustrative purposes only.

I claim:

The ornamental design for a bottle holder, as shown and described.
